UNITED STATES PATENT OFFICE.

HAROLD W. EDEN, OF DETROIT, MICHIGAN, ASSIGNOR TO P. R. MANUFACTURING COMPANY, OF DETROIT, MICHIGAN, A CORPORATION OF MICHIGAN.

ELECTRIC SIGNAL-BELL.

No. 837,673.

Specification of Letters Patent.

Patented Dec. 4, 1906.

Application filed December 26, 1905. Serial No. 293,208.

To all whom it may concern:

Be it known that I, HAROLD W. EDEN, a citizen of the United States, residing at Detroit, county of Wayne, State of Michigan, have invented a certain new and useful Improvement in Electric Signal-Bells; and I declare the following to be a full, clear, and exact description of the invention, such as will enable others skilled in the art to which it pertains to make and use the same, reference being had to the accompanying drawings, which form a part of this specification.

This invention relates to electric signal-bells.

15 It has for its object an improved signal-bell adapted to be used in connection with the high-tension current of an electric light or similar high-tension currents.

In the drawing the figure represents the bell and indicates the wiring.

20 1 indicates the bell; 2, the hammer carried on an armature which is vibrated by the alternate energizing and deenergizing of a magnet 4 14, surrounded by coils 3 and 8.

25 5 indicates the source of electric energy; 6, a direct wire leading to the binding-post 7, thence through the coil 3 and the coil 8. After emerging the conductor from the coil 8

divides. One branch 15 leads to a resistance 9 and thence back to the frame near the 30 lower binding-post 16, and one branch 10 leads to an insulated binding-post 11, thence to a vibrating point 12. The vibrating point 12 is insulated from the hammer-armature 13, but is held to vibrate with it. When 35 the armature 13 is drawn toward the magnets 4 and 14 by their electrical state, the point 12 touches the core 14 of the coil 8, and the current is thereby short-circuited through the point 12 and its connections and through 40 the magnet itself and the frame.

What I claim is—

In combination with a bell, a sounding member adapted to strike thereagainst, a source of electrical energy, a resistance, and 45 a circuit divided between the resistance and the sounding member, one part of the current being short-circuited through said sounding member, substantially as described.

In testimony whereof I sign this specification in the presence of two witnesses.

HAROLD W. EDEN.
